UNITED STATES PATENT OFFICE.

JOHANN LÜTZ, OF BREDENEY, NEAR ESSEN-ON-THE-RUHR, GERMANY.

SHAFT-FURNACE FOR COKING AND GASIFYING COAL.

1,164,295.

Specification of Letters Patent.

Patented Dec. 14, 1915.

Application filed June 19, 1912. Serial No. 704,597.

To all whom it may concern:

Be it known that I, JOHANN LÜTZ, a citizen of the German Empire, and resident of Bredeney, near Essen-on-the-Ruhr, Germany, have invented certain new and useful Improvements in Shaft-Furnaces for Coking and Gasifying Coal, of which the following is a specification.

My invention relates to a shaft-furnace for 10 coking and gasifying coal, having an exterior and an interior heating system.

This furnace comprises a vertical coke-oven wherein the oven proper has an annular section and is surrounded on the outside by 15 heating flues and surrounds similar flues adjacent to its interior. This arrangement has the advantage that the coke-oven can be given a great height, so that the oven not only has a greater capacity but also produces 20 a denser coke. A further advantage arises in that the coke-oven may be readily incorporated in the outer framework of a coal-tower or athanor, so that charging wagons are unnecessary and the coal may be directly 25 fed from the hopper in the tower into the coke-oven. The coal above the cover of the oven may in this way form a gas-tight joint at the top of the coke-oven. These coke-ovens can be built both as recuperative as 30 well as regenerative ovens. The combustion air for the inner heating flues can therefore be preliminarily heated by devices located in the inner portion of the oven, while the devices for preliminarily heating the air for 35 the outer heating flues can be located, when the ovens are built alongside of one another, in the intervening spaces between the ovens. Tube recuperators are preferably employed, by way of example, for preliminarily heating 40 the air which are vertically arranged both within the oven itself and also in its upper tapered portion. In order to further utilize the heat of the issuing combustion gases, they are preferably led, after having given 45 a portion of their heat to the air in the tube recuperator, through a further tube recuperator in which the remaining heat is given up to the combustion gas.

The lower end of the annular coke oven is 50 formed by an annular bottom, which has an upwardly tapering section and slides over the interior portion of the oven. This bottom is rendered gas-tight either by stuffing-box or by a water-joint. On the bottom being 55 lowered, water is admitted to a pipe and in powerful jets is inwardly directed therefrom

against the descending coke-cake. By this means the coke-cake is split up, and the coke being thus quenched is thereupon taken away on a conveyer belt. The heating flues can be 60 arranged in known manner to extend directly upward.

One illustrative embodiment of my invention is represented by way of example in the accompanying drawings, wherein:

Figure 1 is a sectional elevation of the coke-oven, Fig. 2 is a sectional plan of the same, Fig. 3 is a sectional detail view of one form of annular bottom, Fig. 4 is a similar view of another form of bottom.

In these drawings the combustion gases are by way of example passed through tube recuperators. The coke-oven *a* has an annular cross-section and is heated by means of the outer heating flues *b* and the inner 75 heating-flues *c*. The products of combustion from the inner flues pass through the tubes *d* of the tube recuperator in the interior of the oven, and the products of combustion from the outer flues through the 80 tubes *e* to the recuperators located outside the oven. The combustion air, entering from the culvert *f*, passes into the spaces *g* or the ducts *h* before reaching the burner-nozzles for the heating flues, and this air 85 becomes heated in known manner by the issuing combustion gases moving in tubes *d*. The ascending air passes upward and outward from the tops of the spaces *g* to the bottom of the inner flues *c* by suitable canals. 90 The products of combustion issue from the tops of the inner flues *c* to the top of the tube *d*, and downwardly to the outlet. The lower end of the oven is closed by means of the annular upwardly tapering bottom *i*, 95 arranged to be slidable on the center portion of the oven and rendered gas-tight therefrom either by a water joint *k* or a stuffing-box *l*. (Fig. 4.) On the bottom being lowered a powerful stream of water from the water-pipe *m* is directed inwardly against the coke-cake, the latter being thus broken 100 in pieces, and the coke formed is then carried away on the conveyer belt *n*. The bottom *i* of the oven is preferably supported 105 by hydraulic means.

The entire oven is built within the outer iron framework of a coal-tower or athanor whose vertical supports *o* may for example be of a hollow form in order to carry away 110 the discharged steam. The coal can be fed from the hopper *p* of the coal-tower di-

rectly into the coke-oven *a*. The coal above the cover *g* can consequently form the means of closing the upper portion of the oven. The intermediate space between the ovens, 5 and between the ovens and the outer structure of the coal-tower, is filled up with a suitable heat-insulating material, *e. g.* ashes, so that the whole forms a compact well insulated mass, and the pressure from within on 10 the wall of the coke-oven due to the mass of coal contained therein is resisted by the inwardly directed pressure due to the mass of ashes.

I have described one embodiment of my 15 invention, but it is clear that numerous changes could be made in the details thereof without departing from its spirit as defined by the following claims:

I claim:

- 20 1. A coke-oven having a vertical coking chamber of annular cross-section, vertical heating-flues at the inner side of said chamber, and vertical heating-flues at the outer side of said chamber, said inner and outer flues being independent of each other.
- 25 2. A coke-oven having a vertical coking chamber of annular cross-section, a vertically-movable bottom for said chamber, having an outwardly downwardly inclined upper face, and an interior downwardly-projecting-shell, and a water-seal inclosing said shell.
- 30 3. A coke-oven having a vertical coking chamber of annular cross-section, vertical heating-flues at the inner side of said chamber, vertical heating-flues at the outer side of said chamber, heating devices, said inner and outer flues being independent of each other, a core, and a vertically-movable bot-

tom for said coking-chamber, guided on and 40 secured gas-tight to said core.

4. A coke-oven having a vertical coking-chamber of annular cross-section, vertical heating-flues at the inner side of said chamber, vertical heating-flues at the outer side 45 of said chamber, heating devices, said inner and outer flues being independent of each other, a core at the center of the oven, and means in said core for preliminarily heating the air for combustion in the inner heating 50 flues.

5. A coke-oven comprising a tower having hollow supporting posts, a coking-chamber within said tower, said coking-chamber being of annular cross-section, vertical heating-flues at the inner side of said chamber, vertical heating flues at the outer side of said chamber, and heating devices for said flues, said inner flues being independent of the outer flues, pits below the coking-chamber, and conduits connecting the pits with the hollow posts of the tower.

6. A coke-oven comprising a tower having posts, and an exterior wall therebetween, a vertical, annular shell within the tower wall, 65 heating-flues, at the inner side of the shell, heating-flues at the outer side of the core, the space between said shell and core forming a coking-chamber, heating devices, and a filling of boiler ashes in the space between 70 the exterior wall and the shell.

In testimony, that I claim the foregoing as my invention, I have signed my name in presence of two subscribing witnesses.

JOHANN LÜTZ. [L. S.]
